UNITED STATES PATENT OFFICE.

FRANK TORRES, OF EL PASO, TEXAS.

FLYING-MACHINE.

1,289,967.

Specification of Letters Patent. Patented Dec. 31, 1918.

Application filed December 14, 1917. Serial No. 207,166.

To all whom it may concern:

Be it known that I, FRANK TORRES, a citizen of the United States of Mexico, residing at El Paso, in the county of El Paso and State of Texas, have invented new and useful Improvements in Flying-Machines, of which the following is a specification.

This invention relates to flying machines of the heavier than air type, the object in view being to produce a flying machine or airplane of superior lifting and carrying qualities and having accommodation for a large number of passengers or a considerable quantity of freight, the machine being also adapted for military purposes such as bomb carrying and dropping, or the transport of soldiers.

The machine embodies in conjunction with a body of novel streamline formation, fore and aft sets of wings or planes, stabilizing means, and two sets of propellers, one set for lifting and sustaining the machine in the air, permitting the speed of the machine to be greatly reduced even to the hovering point, and another set of propellers used for propelling the machine through the air in the normal line of flight.

The invention also contemplates a novel arrangement of means for imparting a high degree of stability to the machine as a whole.

With the above and other objects in view, the invention consists in the novel construction, combination and arrangement of parts, herein described, illustrated and claimed.

35 In the accompanying drawings:—

Figure 1 is a plan view of the improved flying machine.

Fig. 2 is a side elevation of the same.

Fig. 3 is a front elevation thereof.

40 The improved machine comprises a body or fuselage 1 the rear portion of which, in rear of the front plane, is of the conventional streamline formation as shown in Figs. 1 and 2. The forward portion of the body is substantially wedge shaped in plan as shown in Fig. 1 with the exception of the extreme forward part thereof which is in the form of a pointed prow 2 forming a cock pit 3 in which is arranged the aviator's seat 4 and the controls of the machine.

Just in rear of the aviator's seat 4, I mount

a forward engine 5 the shaft 6 of which is connected by means of gears 7 and 8 to a pair of oppositely extending countershafts 9 in turn connected by gears 10 and 11 to a pair of forwardly diverging propeller shafts 12 which are journaled in bearings and housed within the forwardly expanding portion of the body or fuselage 1 as clearly indicated in the plan view. On the forward extremities 55 of the propeller shafts 12, I mount tractor propellers 13.

In the aft portion of the fuselage, I mount a rear engine 14 the shaft 15 of which extends in front and in rear of said engine and 60 is connected by gears 16 and 17 to a pair of elevating propellers 18. The propeller shafts 19 extend vertically through the bottom of the fuselage and the propellers 18 are arranged under said body as shown in Fig. 2. 70 Bearings 20 for the propeller shafts 19 are located at a distance below the body 1 and close to the propellers 18 and are held by oblique braces 21. Rotary weighted members 22 are carried by the shafts 6 and 15 75 and by rapid rotation they act to equalize the torque of said shafts and also assist in maintaining the stability of the machine as a whole.

The front wings 23 extend in substantially 80 horizontal planes from the opposite sides of the triangular forward portion of the body 1 and are braced by means of stays 24 which are connected at their outer extremities to the wings 23 and at their inner extremities 85 to vertical members 25 of the landing gear or wheel base as indicated in Fig. 3. Other stays 26 are connected at their outer extremities to the wings 23 and are connected at their inner extremities to a mast 27 which 90 rises from the body or fuselage 1.

In rear of the front wings 23, I arrange a rear set of wings 28. These wings are of bird like formation having rounded or convex leading edges 29 and flexible trailing 95 edges 30 closely resembling a bird's wing. The ribs of the rear wings 28 are flexible and particularly the rear portions of said ribs, corresponding with a bird wing structure. Furthermore the rear wings have 10 greater camber than the front wings so that greater lift is obtained on the rear wings

- while proceeding at a comparatively low speed than when flying at a greater speed, at which time greater speed the wings tend to flatten out and diminish in curvature and camber due to the increased pressure against the bottom surfaces of said rear wings 28. This also enables the machine to make a landing at a lower speed than will be possible under a rigid wing structure of the necessary low degree of camber for traveling at high speeds. The rear wings 28 are braced by stays 31 attached at their outer extremities to said wings and attached at their inner extremities to vertical members 15 of the wheel base or landing gear. Other stays 32 are attached at their outer extremities to the wings 28 and at their inner extremities to a mast 33 rising from the body or fuselage 1. The masts 27 and 32 are further braced in a fore and aft direction by forwardly and rearwardly extending stays 34 and 35 as shown in Fig. 2.
- The wheel base or landing gear comprises a forward set of wheels 35 mounted upon an axle 36 carried by a forward frame like structure 37 having combined therewith one or more skids 38. A single supporting wheel 39 is arranged under the rear portion of the body 1 and attached thereto by a frame structure 40. Another intermediate wheel 41 is located centrally below the body 1 and is carried by a frame structure 42 extending downwardly from the body 1. The wheels 35, 39 and 41 are arranged to simultaneously rest upon the ground preparatory to and after flight. At such time, the longitudinal axis of the body or fuselage 1 is at an inclined angle with relation to the ground surface.
- In conjunction with each of the forward wings 23, I use a horizontal rudder 43 hinged at 44 on a horizontal axis, and a vertical rudder 45 hinged at its forward edge 46 on a vertical axis and formed with a slot 47 through which the adjacent horizontal rudder 43 extends, enabling the vertical rudder 45 to be swung to either side. The rudders 43 and 45 are controlled and operated by suitable connections leading to levers 48 and 49 in the aviator's cockpit 3.
- The rudders 43 act both as horizontal rudders, ailerons or stabilizers, it being readily apparent that by simultaneously depressing the trailing edges of both rudders 43, the front of the machine is elevated and directed upwardly as when taking an ascending angle. In order to set the machine in a volplaning angle, the trailing edges of the rudders 43 are elevated, thus serving to depress the forward portion of the machine. The lateral equilibrium of the machine is controlled by depressing the trailing edge of the rudder 43 on the low side and elevating the trailing edge of the rudder 43 on the high side of the machine. By turning the vertical rudders 45 to the left, the forward part of the machine is caused to veer to the right and conversely by swinging the trailing edges of the vertical rudders to the right, the forward part of the machine is caused to veer to the left, thus the machine may be steered to the right or the left by the means described.
- From the foregoing description taken in connection with the accompanying drawings it will be seen that I have produced a flying machine or airplane having fore and aft sets of wings which add to the carrying capacity of the machine. The stabilizing surfaces are carried by the front wings rendering the use of operating connections therefor possible. The propellers 13 are of course employed to propel the machine along the ordinary path of flight while the propellers 18 act in the nature of helicopter screws, exerting a direct downward pressure and a direct uplift of the body of the machine. This enables the speed of the propellers 13 to be reduced or they may be entirely stopped in order that the machine as a whole may proceed at a comparatively low speed or the speed of the machine reduced to the hovering point. It is of course intended to provide both engines with the ordinary throttling means so that either engine may be allowed to turn at full speed or the speed thereof may be reduced according to requirements. It is intended of course to use the lifting propellers 18 when rising from the ground and until the desired altitude is obtained. Thereafter the propellers 18 may be slowed down or entirely stopped, as the machine may then maintain itself in flight with the aid of the propellers 13 alone. The use of the lifting propellers 18, however, in conjunction with the automatic increase in the camber of the rear wings 28 when proceeding at low speed, will enable the machine to land safely at a greatly reduced speed in a forward direction.
- It will also be observed that by reason of the angular disposition of the tractor propellers 13, blasts of air are directed against the body or fuselage 1, which blasts of air therefore act with a squeezing action on the body which results in a material reduction in the head resistance of the machine. This results in a material increase in the speed of the machine as compared with the ordinary arrangement of tractor or pusher propellers.
- I claim:
- In a flying machine, the combination of a body of streamline formation, supporting wings extending in opposite directions therefrom and arranged in tandem formation, an engine mounted within the body, lifting propellers located under the body and connected

by vertical shafts to said engine shaft, another engine mounted within the body, a pair of tractor propellers arranged at the forward end of the body in advance of the 5 wings, and rearwardly converging shafts for said tractor propellers, the last named shafts being geared to and driven by the last named

engine, the front wing having a constant camber and curvature and the rearwardly disposed wings being flexible and of automatically variable camber.

In testimony whereof, I affix my signature.

FRANK TORRES.
